UNITED STATES PATENT OFFICE.

SAMUEL COFFIN, OF HIGH POINT, NORTH CAROLINA.

SHAFT-HANGER.

SPECIFICATION forming part of Letters Patent No. 601,885, dated April 5, 1898.

Application filed November 29, 1897. Serial No. 660,139. (No model.)

To all whom it may concern:

Be it known that I, SAMUEL COFFIN, a citizen of the United States, residing at High Point, in the county of Guilford and State of North Carolina, have invented certain new and useful Improvements in Shaft-Hangers; and I do declare the following to be a full, clear, and exact description of the invention, such as will enable others skilled in the art to which it appertains to make and use the same.

My invention has relation to shaft-hangers; and the object is to provide a hanger in which the bearing is universal and self-adjusting and also adjustable independent of its automatic or self adjustment.

With this object in view the invention consists of certain features of construction and combination of parts, which will be herein-after fully described and claimed.

In the accompanying drawings, Figure 1 is a perspective view of a shaft-hanger. Fig. 2 is a longitudinal sectional view through the same parts. Fig. 3 is a detail perspective view of one section of the bearing, and Fig. 4 is a similar view of one section of the bearing-case.

In said drawings, 1 denotes the stationary frame of the hanger, 2 the casing supported therein, and 3 the bearing supported in the casing.

The casing consists of two counterparts *a* and *b*, each having a semicircular grooved recess 4 and provided with corresponding lugs and recesses 5 and 6 to lock the parts together against lateral displacement. The casing is supported in the frame 1 by means of four set-screws 7, whereby the casing may be adjusted vertically or laterally.

The bearing consists of two counterpart sections *c c'*, provided along their edges with coacting recesses *d e*. The inner diameter of the outer ends of the bearing-sections when placed together are adapted to correspond with the diameter of the shaft, and the intermediate interior portions are hollowed out to form an annular hollow chamber. On the outside the bearing-sections are formed with semicircular convex bulges, which correspond with the grooves of the casing. These bulge portions are surrounded by the walls of the

semicircular grooves and permit of the bearing rocking in all directions, while at the same time preventing it from becoming accidentally disengaged.

Oil-cups 8 are arranged at each end of the bearing and supply oil to the hollow space therein.

While I do not wish to be confined to the particular manner of engaging the set-screws of the frame with the casing, I prefer the construction shown in the drawings, in which the casing is formed with a groove that extends entirely around it and receives the inner ends of the set-screws, thereby forming a sort of lock and preventing the casing slipping in a lateral direction, when the screws are engaged, should the screws become slightly loosened.

Although I have specifically described the construction and relative arrangement of the several elements of my invention, I do not desire to be confined to the same, as such changes or modifications may be made as clearly fall within the scope of my invention without departing from the spirit thereof.

Having thus described my invention, what I claim, and desire to secure by Letters Patent, is—

1. In a shaft-hanger, the combination with a two-part casing, each part having a semicircular groove and coacting lugs and recesses, of a bearing consisting of two parts having coacting ribs and grooves, and provided with semicircular convex bulges to seat in the grooves of the casing, and provided with an interior oil-chamber, substantially as set forth.

2. In a shaft-hanger, the combination with a frame provided with radially-disposed set-screws, of a two-part casing supported in said frame, and provided with an annular central groove, and a two-part bearing having an annular curved bulge to fit in said groove to form a ball-and-socket joint, substantially as set forth.

In testimony whereof I hereunto affix my signature in presence of two witnesses.

SAML. COFFIN.
